United States Patent Office

Des. 217,999
Patented July 7, 1970

217,999

GUN CASE

Paul Belokin, Jr., 6919 W. 43rd St.,
Berwyn, Ill. 60402

Filed Mar. 24, 1969, Ser. No. 16,404

Term of patent 14 years

Int. Cl. D3—01

U.S. Cl. D87—1

FIG. 1

FIG. 2

FIG. 3

FIG. 4

FIG. 5

FIG. 6

FIG. 1 is a top plan view of a gun case, showing my new design;

FIG. 2 is a side elevational view, the opposite side being substantially a mirror image thereof;

FIG. 3 is a bottom plan view;

FIG. 4 is a barrel end elevational view;

FIG. 5 is a stock end elevational view; and

FIG. 6 is a perspective view thereof with the stock end cover partly open.

I claim:

The ornamental design for a hand gun case, as shown and described.
